UNITED STATES PATENT OFFICE.

FREDERICK WILLIAM GARNER, OF ISLINGTON, ENGLAND.

COIN-DISPLAYING DEVICE.

1,122,493.

Specification of Letters Patent. Patented Dec. 29, 1914.

Application filed October 21, 1912. Serial No. 727,059.

To all whom it may concern:

Be it known that I, FREDERICK WILLIAM GARNER, a subject of the King of Great Britain, residing at Islington, in the county 5 of Middlesex, England, have invented new and useful Improvements Relating to Coin-Displaying Devices for Use with Tills and the like, of which the following is a specification.

10 This invention has reference to coin-dis-
playing devices for use with tills and the
like and more particularly to coin display-
ers of the type which are employed with the
now well known cash register tills. Such
15 displayers consist of a revoluble wheel
mounted in a casing and having divisions
in each of which a single coin is adapted to
rest and be displayed through the transpar-
ent front of the device said wheel being
20 so connected with the operating mechanism
of the cash register that each time a key
is depressed the aforesaid wheel is rotated
one step. Now the object of providing these
displayers in connection with a till is to
25 minimize the risk of dispute arising between
the retailer and the customer for instance
where the retailer gives change for a half
dollar piece and the customer is under the
impression that he tendered a dollar piece
30 the point can be settled owing to the fact
that the coin is exposed to view in the dis-
player but owing to the fact that the revol-
uble wheel is moved one step forward each
time a key of the register is depressed
35 whether a coin has been placed in the dis-
player or not the object of the device is de-
feated for it will be apparent that it fre-
quently happens in a busy establishment
that a coin placed in the display will be
40 passed through it and into the till so rapidly
owing to the register having been used for
giving change for coins of other value that
the coin is lost to view before any dispute
as to its denomination can be satisfactorily
45 adjusted.

Now the object of the present invention is
to provide an improved coin display which
shall be independent of the operating mecha-
nism of the till or cash register and in which
50 the wheel is moved one step only when a
coin of the predetermined denomination is
inserted therein thus allowing such coin to
be displayed for a much longer period than
has hitherto been the case.

55 In its broadest aspect the invention con-
templates a construction in which a rota-

table coin displaying wheel is independent
of the cash register mechanism and is adapt-
ed to be moved one step by the depression
of the coin chute in the act of inserting a 60
coin.

The invention also comprises details of
construction and arrangement of parts all as
more specifically hereinafter described and
finally pointed out in the claiming clauses. 65

In order that the invention may be readily
understood and carried into effect by those
skilled in the art to which it appertains the
same will now be described in detail for
which purpose reference is to be had to the 70
accompanying drawings in which:

Figure 1 is a front elevation of a coin dis-
playing device embodying this invention
and Fig. 2 is a rear elevation of the same.
Fig. 3 is a front elevation of the coin dis-
player the front plate of the casing *a* (Fig.
1) being removed to show the arrangement
of the wheel. Fig. 4 is a fragmentary view
similar to Fig. 2 but drawn to a larger scale
the cover plate of the operating mechanism 75
being removed to more clearly illustrate the
mechanism for rotating the coin displaying
wheel upon the insertion of a coin.

A display constructed in accordance
with this invention comprises a casing *a* 85
which may be secured upon a box or till *b*.
Rotatably mounted upon a spindle *c* within
the casing *a* is a coin displaying wheel *d*
having in the construction shown six com-
partments or divisions formed by the 90
spokes *e*—*e*⁶ located between two disks *f* of
mica, celluloid or other transparent mate-
rial. The spindle *c* carries a spur wheel *g*
(seen more clearly in Fig. 4) the teeth of
which are engaged by a spring controlled 95
pawl *h* pivotally mounted at *h* at the end
of a lever *i* pivoted at *j* to the casing *a*. The
pawl *h* is held in the position shown in full
lines in Fig. 4 by a leaf spring *k* which
presses the tail *h*² of the pawl against a stop 100
l on the lever *i*. Pivotally secured at *m* to
the lever *i* is an operating lever *n* which is
positively attached by its opposite end to
the coin chute *o* the lever *n* being slotted as
at *p* to admit of its being depressed to ro-
tate the wheel *d* while a spring *p'* is pro-
vided to return the parts to the normal po-
sition all as will be presently explained. 105

The operation of the improved coin dis-
player is as follows reference being had 110
more particularly to Fig. 4:—When a coin
is inserted in the chute *o* this latter is

pressed downward by the fingers so depressing levers *n* and *i* and allowing pawl *h* to turn about its pivot *h'* and escape the teeth of the wheel *g*. The parts are now in the 5 position shown in dotted lines in Fig. 4 where it will be seen that the pawl *h* is located beneath one of the teeth of the wheel *g*. Upon removing the fingers from the 10 chute *o* the spring *p'* raises levers *n* and *i* and the pawl *h* causes the spur wheel *g* to be rotated one tooth and the coin located between the spokes *e²* and *e³* as shown in dotted lines is carried around into the 15 position shown in full lines and remains exposed to view through the transparent disks *f*. Upon another coin being inserted through the chute *o* which is of course depressed in the act of inserting such coin the cycle of operations is repeated and the 20 displaying wheel again moved one step. Upon the coin first inserted reaching the position *q* Fig. 3 it falls through the aperture *r* into the box *b*.

In order to prevent the displaying wheel 25 *d* turning in the opposite direction a spring *s* having an enlargement *t* thereon adapted to engage between two teeth of the wheel *g* is provided (Fig. 4) while upon the opposite side of the wheel a pivoted dog *u* (Fig. 30 3) is arranged against which the spokes *e'-e⁶* contact as the wheel *d* rotates in the direction of the arrow thus insuring that the wheel *d* shall be moved positively but 35 one step at each actuation of the apparatus.

While I have described the construction 40 of parts and operations preferred various modifications in the details of construction may be effected without departing from the spirit and scope of the invention as expressed in the appended claiming clauses and I therefore do not desire to be limited by the positive terms employed in connection with the description excepting such as 45 the state of the art may require.

I claim:

1. The combination with a casing; of a coin displaying wheel mounted within the casing, a ratchet wheel rotatable with the coin displaying wheel, a lever having one end pivotally connected to said casing, a pawl pivotally mounted on said lever and engaging one of the teeth of the ratchet wheel when the lever is moved in one direction, a spring carried by said lever and 50 pressing against the pawl to permit free movement of the lever in the opposite direction, a coin slide and chute carried by the casing, an arm connecting said chute and lever and a spring connected to said 55 arm and casing to retract the arm and coin chute for depression.

2. The combination with a casing, of a coin display wheel mounted within the casing, a star wheel rotatable with the coin 60 displaying wheel, a lever having one end pivotally secured to said casing, a pawl pivotally secured to the free end of said lever, a stop secured adjacent the end of said lever, a spring secured to the under surface of the lever, having its free end adapted to engage said pawl, said pawl normally engaging said star wheel, a coin receiver, a lever having one end slidably mounted in the casing adjacent said coin-receiver said 65 coin receiver and its free end pivotally mounted in said pawl containing lever, provided intermediate its end with an arm at an angle thereto adapted to receive a spring at its farthest end, and ribs extending 70 beyond the periphery of said coin displaying wheel, a pivoted dog secured to said casing adapted to operatively engage said ribs thereby preventing rotation in two directions of said coin displaying wheel.

FREDERICK WILLIAM GARNER.
